UNITED STATES PATENT OFFICE.

ADELMER M. BATES, OF CHICAGO, ILLINOIS, ASSIGNOR TO BATES VALVE BAG COMPANY, OF CHICAGO, ILLINOIS, A CORPORATION OF WEST VIRGINIA.

MACHINE FOR FILLING BARRELS, BAGS, AND PACKAGES.

1,269,777.

Specification of Letters Patent. Patented June 18, 1918.

Application filed February 2, 1914. Serial No. 815,920.

To all whom it may concern:

Be it known that I, ADELMER M. BATES, a citizen of the United States, residing at Chicago, in the county of Cook and State of Illinois, have invented a certain new and useful Improvement in Machines for Filling Barrels, Bags, and Packages, of which the following is a specification.

My invention relates to improvements in package filling machines and is illustrated more or less diagrammatically in one form in the accompanying drawings, wherein

Fig. 1 is a side elevation;

Fig. 2 is a plan view;

Fig. 3 is a section along the line 3—3 of Fig. 2;

Fig. 4 is a front elevation in part section of the barrel holding part alone;

Fig. 5 is a section along the line 5—5 of Fig. 2;

Fig. 6 is a longitudinal section on Fig. 2;

Fig. 7 is a section along the line 7—7 of Fig. 3;

Fig. 8 is a section along the line 8—8 of Fig. 5;

Fig. 9 is a section along the line 9—9 of Fig. 8;

Fig. 10 is an enlarged detail in part section of the clutch mechanism shown in Fig. 1;

Fig. 11 is a section along the line 11—11 of Fig. 10; and

Fig. 12 is a section along the line 12—12 of Fig. 10.

Like parts are indicated by the same letter in all the figures.

The self-contained rigid main frame A which is made up of side members and cross tie members as indicated and is supported on the supporting legs A¹ supports at its top a propeller pocket A² having a tangential discharge or feeding tube A³ and a rotary propeller A⁴. This rotary propeller is mounted on a shaft A⁵ which shaft carries a pulley A⁶ which may be driven from any suitable source of power by belt not here shown. This shaft also carries a pinion A⁷ in mesh with a gear A⁸ on a countershaft A⁹. This countershaft A⁹ has a sprocket A¹⁰ over

which rides a chain A¹¹ to drive a sprocket A¹² on a shaft A¹³ which shaft carries a feed regulating or controlling paddle or wheel A¹⁴ interposed between the feed pocket A² and the filling hopper A¹⁵. The driving connection between the sprocket A¹⁰ and the shaft A⁹ is discontinuous and takes the form of a clutch subsequently to be described.

The tangential passage or feeding tube carries on its outer end a package contacting plate or anvil B¹ in said plate and is surrounded by a heavy boss B² in said plate. This tube extends both forwardly and rearwardly from the propeller or feeding pocket, and the center line thereof is tangential to the inner boundary of the feeding pocket so that half of the tube is above and half of it below the feeding pocket though all communicating therewith. In this tube is slidably mounted a pointed feeding plunger B³, this plunger being thus half in and half out of the feed pocket. The vanes or blades of the propeller A⁴ are notched as indicated at B⁴ in Fig. 7 so that the presence of this plunger in the feed passage and its reciprocation therewith will in no wise interfere with the rotation of the propeller. In order, moreover, that the force of these propeller blades be not wasted on the feeding side as they rotate in the direction shown by the arrow in Fig. 3, there is disposed in the wall of the propeller pocket a peripheral, semicylindrical or semicircular boss B⁵ as shown in Figs. 3 and 7, and this boss closes the aperture B³ as indicated coming down over and merging into the line of the propeller or feed plunger. It will be noted that this plunger or propeller when in the position shown in Fig. 3 closes the opening between the feed pocket and the propeller tube, but that the rearward movement of this plunger would free this passage and permit the propeller to discharge material tangentially from the feed pocket along the tube. This plunger B³ is provided with a head B⁶ and is slidably mounted in what I have called an auxiliary crosshead B⁷. This auxiliary crosshead B⁷ is free to reciprocate on the guide bars B⁸. The plunger B³ is free to reciprocate with re-

spect to this auxiliary crosshead but this reciprocation is yieldingly resisted by the compression springs B⁸ which are interposed between the adjustable nuts B⁹ on the tension bars B¹⁰ and head B⁵ on the plunger B². These tension bars are mounted in the auxiliary crosshead as indicated in Fig. 2 and thus yieldingly hold the plunger in the position shown in Fig. 2 with respect to the auxiliary crosshead. B¹¹ is a crank shaft mounted at the rear end of the frame A and carrying on either end the cranks B¹². It is driven by means of a sprocket B¹³, chain B¹⁴ and sprocket B¹⁵ from the shaft A⁹. B¹⁶ is the main crosshead reciprocally mounted in the guides B¹⁷ on the main frame and adapted to be driven in response to the rotation of the cranks by means of the connecting rods B¹⁸. This crosshead it will be noted is always reciprocating when the machine is operating, but means are provided whereby the connection between it and the auxiliary crosshead is discontinuous.

C is an openwork frame scale beam having knife edges C¹ resting on the blocks C² on the frame A. C³ is an adjustable counterbalance weight on the end of the scale beam. C⁴ is an A-frame supported at its lower end on the knife edges C⁵ on the scale beam C and guided at its upper end by the links C⁶ pivoted to it and the brackets on the main frame A. C⁷ are the horizontal tracks mounted on either side of the A-frame C⁴. C⁸ is a package supporting frame or cradle having at one end rollers C⁹ traveling along the tracks C⁷ and supported at the other end by the links C¹⁰ which are carried by the rod C¹¹ rotatably mounted in the outer end of the tracks C⁷. C¹² is a control lever mounted on the rod C¹¹ limited in its rearward movement by the catch C¹³ and in its forward movement with respect to the frame C⁸ by the stop C¹⁴ thereupon. C¹⁵, C¹⁶ are adjustable supports carried by the package holding frame or cradle whereby the package may be centered so that the filling aperture therein will coincide with the end of the filling tube, thus providing for the filling of different size and shape packages. A description of one of these will suffice for the rest. The sleeve C¹⁷ is mounted on the cradle C⁸. It has slidably mounted therein the support C¹⁸. The cross member C¹⁹ limits the outward movement of the support and has screw-threaded therein the adjusting screw C²⁰ which carries the support. A lock nut C²⁰ is provided. C²¹ are tongues projecting downwardly from the support C¹⁸ on either side of the member C¹⁹ to prevent rotation of the support C¹⁸ and hold it in position. C²² is a barrel clamp. It is supported on the cross member C²³ and adapted to be pressed against the barrel by means of the screw C²⁴. The cross member C²³ is ad-

justably supported on the pivoted supporting rods C²⁵ which rods are pivoted to the A-frame C⁴. In line with these rods and also pivoted on the A-frame are holding links C²⁶ which are pivoted on the main frame A and whose rotary motion with respect to that frame is limited by the stop peg C²⁷ in the recess C²⁸. C²⁹ is a collar slidable along the links C²⁶ and adjustable in position with respect thereto. C³⁰ is a guide and support pin pivoted on the collar C²⁹ and slidable in a lug C³¹ on the A-frame C⁴. C³² is a compression spring interposed between the lug C³¹ and the collar C³³ on the rod or link C³⁰ to yieldingly swing the links C²⁶ into the position shown in dotted lines in Fig. 1 when the barrel clamp is released. It will be noted that the filling tube is smaller than the bunghole of the barrel so that the barrel will be free to move along the anvil plate B and boss B¹ without either opening the bunghole or interference on the part of the filling tube.

D is the feed control lever. This lever is attached to and adapted to actuate a segmental miter gear D¹ in mesh with a further segmental miter gear D² which miter gear carries what is in effect a bell crank arm D³. This arm is in slidable and rotatable engagement with a control rod D⁴ as indicated. This control rod is slidably mounted on the frame A, being guided in particular by the bearing D⁵. Compression springs D⁶ on either side of this bearing tend yieldingly to return this rod to the mid position. It is this rod whose different positions some of them controlled by the operator and some of them automatic, are relied upon to control the different feeding mechanisms. Its first function is to open the feeding tube or throat and permit the passage of material from the propeller pocket through this tube or throat into the package. The bearing D⁵ operates also as a stop in the following manner: This bearing is carried on a lug D⁷ engaged by a boss D⁸ on the frame A. This lug is hollow as indicated and has pivoted therein a latch D⁹ on a fixed pin D¹⁰. The rod contacting end of this latch is pointed as indicated and the distance from the center of the pin D¹⁰ to the pointed end of the latch is greater than the distance from the center of the pin to the surface of the rod. The rear end of the latch is square as indicated and engaged by the spring pressed tappet D¹¹. In the position shown in Fig. 8 the rod D⁴ must be moved from right to left since a movement in the reverse direction would merely clamp it or lock it against the point of the pin, and this movement must continue until the latch point reaches D¹² when it springs down into the neutral position to permit a return movement of the rod. This return movement of the rod must

continue until the slot D¹³ has been reached. Thus, it is not possible to move the rod D⁴ other than through a complete cycle as indicated. D¹⁴ is a cam mounted on the rod D⁴.

5 When this cam is moved to the left its inclined surface is adapted to ride over the cam roller D¹⁵, as this roller together with the lever D¹⁶ which carries it reciprocates back and forth, this lever being mounted on 10 the crosshead B¹⁶. The result of this is that at the extreme movement of the crosshead to the right the roller bearing end of the lever is pressed down and this throws the pin D¹⁷ up so that as the crosshead returns this pin 15 will strike the auxiliary crosshead B⁸ and move it back a sufficient distance to open the communication between the feed pocket and the feed tube. The auxiliary crosshead will rest at this position since the pin D¹⁷ 20 only strikes the front edge of it and cannot bring it back as it reciprocates from left to right. It will be noted that this pin D¹⁷ terminates in a hook D¹⁸ which engages the slot D¹⁹ in the auxiliary crosshead to hold them 25 together and prevent displacement during the time that the movement is taking place, since during this time the pin D¹⁷ is not otherwise supported from the auxiliary crosshead. At the end of this right to left 30 movement the roller D¹⁵ rides on the spring pressed cam or latch D²⁰ which cam or latch is mounted on the bracket D²¹ on the bearing D⁵. This, since the engagement of the hook D¹⁸ with the slot D¹⁹ prevents movement of 35 the lever D¹⁶, will result in compressing the spring D²² and depressing the latch D²⁰. As soon, however, as the main crosshead has reached its farthest left-hand position and commences to return to the right, the 40 hook D¹⁸ is disengaged from the slot D¹⁹ and the spring D²² pressing upwardly on the latch D²⁰ rocks the lever D¹⁶ to draw the pin D¹⁷ down into the position shown in Figs. 5 and 6, thus leaving the auxiliary 45 crosshead and feeding plunger in such position that the discharge of material may take place from the feed chamber through the feeding tube or throat into the package.

The barrel or package then is filled up 50 by the rapidly moving centrifugally driven feed from the propeller chamber, and this feed will rapidly fill the barrel. It, however, does not completely fill it and does not compact it. The operator can tell from the 55 action of the machine or by inspection when the barrel has been filled with as much material as can be packed into it by the rapidly moving, low pressure, paddle driven stream. When the time comes that the barrel is so 60 filled, he moves the lever D to the right and draws the rod D⁴ back to the right. This may be done, of course, because the pin or latch D⁹ has reached the slot D¹² and 65 swung into position so that it no longer interferes. This rotates the control lever E which is in slidable and rotatable relation to the end of the rod D⁴ and the sleeve E¹ is thereby rotated in a clockwise direction carrying with it the finger E² into the position shown in dotted lines in Fig. 6 where it is in the path of the cam weight E³, which weight is normally in the position shown in dotted lines in Fig. 6 and is carried on and reciprocates with the main crosshead. With the parts in this position, on the next complete reciprocation of the crosshead the end of the finger E² strikes the part E⁴ and causes it to rotate to the position shown in full lines in Fig. 6. This rotates the cam E⁴ to permit the cam roller E⁵ to lift slightly from the position 80 shown in dotted lines in Fig. 6 owing to the pressure of the spring E⁶. Thus the shaft E⁷ is rotated in a counterclockwise direction by this spring, and the levers E⁸ thrust the pins or plungers E⁹ up to engage the cams E¹⁰ on the auxiliary crosshead, as shown in Fig. 6. The auxiliary crosshead then commences its reciprocation with the main crosshead, being rigidly connected thereto by these pins. Every time the crosshead 90 then feeds forward the plunger is thrust through the feeding throat into the package compacting the material. When the plunger is withdrawn a tube or aperture is left in the material and through it more material is discharged by the propeller. This process continues gradually compacting the material in the package. In order, however, that this compacting may extend 95 throughout the whole length of the package the springs B⁸ which hold the plunger in position with respect to the auxiliary crosshead are provided and these springs gradually permit the plunger to recede or decrease its travel with respect to the auxiliary 100 crosshead until when the aperture in the package has reached a minimum these springs might possibly be so flexed as to permit the crosshead to make its cycle without forcing the plunger into the barrel at 105 all. By this time the weight of material in the package will be sufficient and the scale beam will tip up. E¹¹ is a stop on the scale beam located in line with the reciprocating cam weight E³ but beneath it. When, however, the scale beam has rotated this stop projects up into the path of the tappet foot E¹², and as the crosshead moves forward this foot strikes this stop and is swung back 115 toward the position shown in dotted lines in Fig. 6. Since, however, this stop does not extend up far enough to swing it clear back, the cam is provided with a high point E¹³. The action of the stop E¹¹ is sufficient to rotate the part E⁴ so that the roller E⁵ 120 comes to the left-hand side of the high point E¹³, whereupon the pressure of the spring E⁶ will be sufficient acting against

the surface E^{14} to complete the movement of the cam back to the dotted line position, whereupon the feeding stops with the plunger left in the position shown in Fig. 3, because there is nothing to draw it out of that position which is the position it assumed when the connection was broken.

It will be understood that during the operation the feed control wheel rotating constantly will tend to keep the feed or propeller pocket and the passage leading thereto from the feed control substantially full of material. Preferably the total capacity of this passage and propeller will be sufficient to exactly supply the package with the desired amount of material needed to be packed in after the centrifugal feed has filled the package as tight as it can, and therefore I provide means whereby when the centrifugal feed is insufficient and the operator shifts the lever to actuate the forced feed the supply of material from the main feed hopper to the propeller pocket will be cut off. This arrangement I will now describe.

F is a stop carried on the rod D^4 , having pins F^1 and F^2 projecting therefrom. These pins are in line with a tappet end F^3 on a lever F^4 . This lever rotates with a rock shaft F^5 which rock shaft carries a clutch controlling lever F^6 . The end of this clutch controlling lever is wedge-shaped as indicated at F^7 . When the rod D^4 is moved to the left the pin F^2 rocks the lever F^3 to the left to swing the lever F^6 away from its operating position. This is done when the machine is started. When the rod D^4 is moved to the right to commence the forced feeding, the pin F^1 strikes the tappet F^3 and swings the lever F^6 into the operating position so that it will disengage the clutch and leave the feed control wheel A^{14} at rest in the position shown in Fig. 3, thus cutting off the supply of material. The sprocket A^{10} which is provided with a cylindrical hub F^{11} is rotatably mounted on the shaft A^9 . To this shaft is rigidly attached a clutch member or head F^8 having an inclined clutching or tooth engaging aperture F^9 in the face thereof opposed to the end of the hub F^{11} . In this hub F^{11} is slidably mounted a pin F^{10} yieldingly pressed outwardly by a spring F^{11} toward the clutch member F^8 so that it may or will when free to move engage the slot F^9 so that as the shaft A^9 is driven it will carry with it the hub F^{11} . This pin F^{10} is slotted as at F^{12} in line with a slot F^{13} in the hub F^{11} . When the lever F^6 has been rocked to the left into the operating position the surface of cam or wedge F^7 will ride along the boss F^{14} until as the hub F^{11} rotates it comes in line with the slots F^{12} , F^{13} . It will then be pressed into them and the wedge F^7 will gradually force the pin F^{10}

back against the compression of the spring, 65 stopping it in about the position shown in Fig. 10, and until this lever F^6 is rocked the pin will be held out and the sprocket will not be driven. It is only necessary to so position the vanes of the control paddle or wheel 70 A^{14} with respect to the position of the sprocket A^{10} that when the sprocket is in the position shown in Fig. 10 one or the other of the sets of vanes will be in the position shown in Fig. 3 to effectually cut off all 75 material from the propeller chamber.

It will be evident that, while I have shown in my drawings an operative device, still many changes might be made in size, shape and arrangement of parts without departing materially from the spirit of my invention. I wish, therefore, that my drawings be regarded as in a sense diagrammatic.

The use and operation of my invention 85 generally described are as follows:

When the package is a barrel and for barrels, the mechanism illustrated is, of course, especially designed. The empty barrel is placed in position in the cradle, and 90 since the cradle is adjustable as indicated, the barrel can be brought to the proper position to bring its small opening or bung-hole directly opposite the feed opening when the barrel is in its elevated or normal position. The barrel then by means of the barrel clamp is securely forced into position against the feed plate as indicated in Fig. 3. Obviously any kind of adjusting mechanism could be employed as also any kind of 100 clamping mechanism. In practice the machine will be set to fill barrels of a given size and will be run for a considerable period on barrels of that size. When barrels of a different size are to be filled, the 105 cradle will be adjusted to the proper position so as to cause the bung-hole and feed opening to register.

If now, the mechanism be set in motion, the first act will withdraw the compressing 110 plunger and open the feed passage from the rotary filling device to the feed opening, whereupon, of course, the filling device being in operation, successive charges of material will be dropped down upon the feeding device and its motion will force a continuous stream of material through the feed passage and feed opening into the barrel or package. This operation is continued until the barrel is substantially full. Then it may continue 115 until the pressure applied by the blades of the filling device will be insufficient to cause any more material to enter the barrel. About this time, automatically, or as here illustrated, by hand, the plunger is set in motion, whereupon a charge of material, being that mass of material which lies in the 120 feed passage, will be forced forward into the

barrel and tend to compress the material in the barrel.

In point of fact, during such operation and after the first few motions of the plunger there will be left in the barrel back of the plunger, as it retreats, a tubular opening, for the contents of the barrel will be sufficiently compressed to cause the opening to remain intact, or as the plunger is withdrawn, the filling device forces forward a quantity of material which fills or tends to fill this opening in the barrel, and thus the charge of material so-called, is extended far beyond the feed passage and into the body of the barrel. The plunger compresses this entire charge and forces it into the barrel against the bottom of such opening and spreads it against the sides so as to increase the pressure on the material within the barrel. This process is continued, the plunger gradually shortening its stroke but being held to its work by the springs until the barrel has received the requisite amount of material.

In a machine where the weighing is done automatically, this will result in a tendency of the barrel to move downwardly because it has attained its predetermined weight. This immediately stops the action of the plunger and the movements are so timed that it stops at a point where it closes the feed passage. This, of course, leaves the mechanism free to permit the barrel to descend and to be discharged and another to be inserted and brought to position and clamped into position, whereupon the operation can be continued.

At the moment when the plunger is set in motion, the supply mechanism is disengaged by the action of the clutch so that no further supply of material is deposited in the rotary feed chamber and the parts are so regulated that at such moment there is just about enough material in the rotary feed chamber to complete the supply necessary to be inserted in the barrel so as to give it the required weight.

I have shown the mechanism necessary to attach a barrel, but for that matter it could be held by hand with its small open mouth or hole in front of the feed opening, or it could be supported in any desired manner or a bag or other package might be substituted for it. To a certain extent at least my machine is applicable to cases where relatively large openings are used for the introduction of the material into the barrel or package, but it is particularly adapted to cases where a single small filling aperture in the package or barrel is employed.

It will be observed that the parts are so set that the continuously acting rotary filler operates to fill the package substantially full with a relatively loose or unpacked mass of

material, and that during the latter portion of such filling operation the plunger or reciprocatory compressing device begins to operate. This motion, however, is intermittent in the sense that it only operates during a portion of the time when the filling means is operating, and also in the sense that it operates to pack the material only on one of its excursions. There is a sense in which the two filling means or the filling and compressing means are simultaneously operating or when their two functions are interrelated. Thus the filling passage and the cavity in the material in the barrel, if any, is alternately filled by the rotary filler and compressed by the reciprocatory compressor. Each device is in a certain sense a filler and each is in a certain sense a compressor, but inasmuch as the special function of the filler is to fill in a short space of time a large quantity of material into the bag and the function of the compressor is to fill or compress a small quantity of material through a considerable length of time into the barrel, I have called one the filler and the other the compressor.

Attention is called to the fact that the parts are so related and connected that the rotary filler is a high speed device, while the compressor is a low speed device. In other words, in the form of the apparatus shown, I first fill at a high rate of speed a large quantity of material into the bag through a small opening by the action of a rotary filler and then compress successive small charges of the material slowly, driving them under through the feed opening by means of a reciprocatory device.

The plunger is itself a cut-off, though, of course, any other cut-off device could be employed. There must be a cut-off at the time when the barrels or packages are being substituted. In this case the plunger acts both as a cut-off and a filling compressor. The supply cut-off is preferably provided and operated as indicated, although the machine might operate satisfactorily without any such supply cut-off.

I do not wish to be limited to the particular form, size, shape, arrangement and relation of all of the parts shown, as these may be greatly altered without departing from the spirit of my invention. I am endeavoring to show one form of structure in which my invention is illustrated, and of course some of its features could be dispensed with without affecting the use and operation of the other element.

Briefly to review the use and operation, we may suppose that the barrels are of a predetermined weight and size and that the scale has been set to respond when a certain amount of material has been inserted in the barrel. The plunger will be supposed

to be at the point where the flow of material through the passage is cut off. The barrel is put in the cradle brought to position and clamped. The first motion of the lever retracts the plunger so as to cause it to free the passageway from the rotary feeder to barrel and the clutch is operated so as to permit the supply feeder to operate. The rotary feeder now fills the barrel swiftly through the small hole, and when the operator thinks the moment has arrived for compressing the contents of the barrel he throws the lever so as to set the compressing plunger into operation. As soon as the barrel is so far filled as to reach its predetermined weight, the scale beam rises, the barrel descends and the plunger is cut out of operation, being left at the point where it closes the passageway.

20 I claim:

1. A package filling machine comprising means for holding the package, means for loosely filling the package substantially full of material and means operative during the latter portion of the filling operation for forcing material into the package to completely fill it with compressed material.

2. A package filling machine comprising means for holding the package, means for completely filling the package with a loose uncompressed mass of material and means operative after the package has been so filled for compressing the material in the package and adding material during such compression to completely fill the package with a mass of closely compacted compressed material, both of said filling means comprising in part a single unitary conduit.

3. A package filling machine comprising means for holding the package, rotary means for loosely filling the package substantially full of material and reciprocating means operative during the latter part of the filling operation for forcing material into the package to completely fill it with compressed material.

4. A package filling machine comprising means for holding the package, continuously operating rotary means for loosely filling the package substantially full of material and reciprocating means operative during the latter part of the filling operation for forcing material into the package to completely fill it with compressed material, a single conduit in communication with the package and with both filling means.

5. A package filling machine comprising means for holding the package, continuously acting means for loosely filling the package substantially full of material and intermittently acting means operative during the latter part of the filling operation for forcing successive charges of material into the

package to completely fill it with compressed material.

6. A package filling machine comprising means for holding the package, continuously acting means for loosely filling the package substantially full of material and intermittently acting means operative during the latter part of the filling operation for forcing successive charges of material into the package to completely fill it with compressed material, a single conduit in communication with the package and with both filling means.

7. A package filling machine comprising means for holding the package, continuously acting rotary means for loosely filling the package substantially full of material and intermittently acting reciprocating means operative during the latter part of the filling operation for forcing successive charges of material into the package to completely fill it with compressed material.

8. A package filling machine comprising means for holding the package, continuously acting rotary means for loosely filling the package substantially full of material and intermittently acting reciprocating means operative during the latter part of the filling operation for forcing successive charges of material into the package to completely fill it with compressed material, a single conduit in communication with the package and with both filling means.

9. A package filling machine comprising means for holding a package, a small filling passageway leading thereto positioned for registry with the package, a rotary filler, a housing therefor, an outlet leading from the housing to such passageway and a plunger reciprocating in such passageway past said outlet.

10. A package filling machine comprising means for holding a package, a small filling passageway leading thereto positioned for registry with the package, a rotary filler having a plurality of fan blades, an outlet leading from the housing to such passageway and a plunger reciprocating in such passageway past said outlet, the blades of said rotary filler being notched to permit the free passage of the plunger.

11. A package filling machine comprising means for holding a package, a small filling passageway leading thereto positioned for registry with the package, a continuously driven rotary filler, a housing therefor, an outlet leading from the housing to such passageway and an intermittently driven plunger reciprocating in such passageway past said outlet.

12. A package filling machine comprising means for holding a package, a small filling passageway leading thereto positioned for

- registry with the package, a continuously driven rotary filler, a housing therefor with an outlet leading from the housing to such passageway and an intermittently driven plunger reciprocating in such passageway past said outlet and means for bringing said plunger to rest in the passage to close such outlet.
13. A package filling machine comprising means for holding the package having a small filling passageway leading thereto, a continuously driven rotary filler with an outlet leading to such passageway and an intermittently driven plunger reciprocating in such passageway past said outlet and means for bringing said plunger to rest in the passage close to such outlet and means for then retracting the plunger to open the outlet.
14. A package filling machine comprising means for holding the package, means for loosely filling the package substantially full of material and means containing a yielding driven connection operative during the latter part of the filling operation for forcing material into the package to completely fill it with compressed material.
15. A package filling machine comprising means for holding the package, rotary means for filling the package substantially full of material and reciprocating means containing a yielding driving connection operative during the latter part of the filling operation for forcing material into the package to completely fill it with compressed material.
16. A package filling machine comprising means for holding a package, a small filling passageway leading thereto positioned for registry with the package, rotary means for loosely filling the package substantially full of material, a plunger and means operative during the latter part of the filling operation for reciprocating it to force material into the package to completely fill it with compressed material, a feed supply cut-off and means for simultaneously retracting the plunger and opening the supply cut-off.
17. A package filling machine comprising means for holding the package, a small filling passageway leading thereto positioned for registry with the package, rotary means for loosely filling the package substantially full of material, a plunger and means operative during the latter part of the filling operation for reciprocating it to force material into the package to completely fill it with compressed material, a feed supply cut-off and means for simultaneously retracting the plunger and opening the supply cut-off, a scale beam on which the package rests and means whereby the movement of the scale beam throws the plunger out of operation.
18. A package filling machine comprising means for holding the package, a small filling passageway leading thereto positioned for registry with the package, rotary means for loosely filling the package substantially full of material, a plunger and means operative during the latter part of the filling operation for reciprocating it to force material into the package to completely fill it with compressed material, a feed supply cut-off and means for simultaneously retracting the plunger and opening the supply cut-off, a scale beam on which the package rests and means reciprocating it the movement of the scale beam throwing the plunger out of operation when it is in a position closing the outlet.
19. A package filling machine comprising means for holding the package, means for quickly filling the package with loose material through a small opening and means for then slowly compressing the material within the package by introduction under pressure of successive charges.
20. A package filling machine having a substantially fixed and horizontally disposed feeding tube, said tube being held against longitudinal displacement, and means for clamping the package in filling register therewith and supporting it against horizontal displacement.
21. A package filling machine having a substantially fixed and horizontally disposed feeding tube, said tube being held against longitudinal displacement, adjustable package supporting means adjacent thereto and means for clamping a package upon said supporting means and in filling register with said tube and supporting it against horizontal displacement.
22. A package filling machine having a horizontally disposed feeding tube and means for clamping the package in filling register therewith and supporting it against horizontal displacement.
23. A package filling machine having a horizontally disposed feeding tube, said tube being held against longitudinal displacement, adjustable package supporting means adjacent thereto and means for clamping a package upon said supporting means and in filling register with said tube and supporting it against horizontal displacement.
24. A barrel support for filling machines and the like comprising a cradle and three separate adjustable barrel supporting heads carried thereby, one of said heads being located adjacent one end of and directly beneath the barrels, the other two being separated one from the other and located adjacent the other end thereof.
25. A barrel support for filling machines and the like comprising a cradle, a plurality

- of separate barrel supporting heads carried thereby, means for adjustably moving said heads separately along lines intersecting at a common horizontal axis and means for locking them in position.
26. A barrel support for filling machines and the like comprising a cradle and a plurality of separate adjustable barrel supporting heads carried thereby, one of said barrel supporting heads having two widely separated barrel contacting fingers.
27. A barrel support for filling machines and the like comprising a cradle and a plurality of separate adjustable barrel supporting heads carried thereby, each of said barrel supporting heads having a plurality of separate barrel contact fingers.
28. In a package filling machine a frame, a filling tube, a movable package support, a link interposed between the support and frame and a package clamping device mounted on the support.
29. In a package filling machine a frame, a filling tube, a movable package support, a link interposed between the support and frame and a package clamping device mounted on the support, said device having an adjustable package engaging member adjustably mounted thereon.
30. In a package filling machine a frame, a filling tube, a movable package support, a link interposed between the support and frame and a package clamping device mounted on the support and yielding means for normally holding it in an inoperative position.
31. In a package filling machine a frame, a filling tube, a movable package support, a link interposed between the support and frame and a package clamping device mounted on the support, said device having an adjustable package engaging member adjustably mounted thereon and yielding means for normally holding said device in an inoperative position.
32. In a package filling machine a feed tube, a flat shield surrounding it, a movable package support and means independent of the position of said support for forcing the package against said shield.
33. In a package filling machine a scale beam, a horizontal track carried thereby and a package carrying cradle mounted upon said track.
34. In a package filling machine a scale beam, a horizontal track carried thereby and a package carrying cradle mounted upon said track and means for moving said cradle along said track and rotating it with respect to said track.
35. In a package filling machine a scale beam, a horizontal track carried thereby, a package carrying cradle mounted at one end
- upon said track and free to travel therealong and supported at the other end by a lever 65 pivoted at one end on the track and at the other end on the cradle.
36. In a package filling machine a scale beam, a horizontal track carried thereby, a package carrying cradle mounted at one end 70 upon said track and free to travel therealong and supported at the other end by a lever pivoted at one end on the bracket and at the other end on the cradle and means for rotating said lever to slide said cradle along 75 the track and to raise the load upon one end thereof.
37. In a package filling machine, package clamping means comprising a package engaging member, a supporting frame therefor, an adjustable connection between said frame and member and an adjustable tension support for said frame.
38. In a package filling machine having a horizontally disposed filling tube, means for 85 pressing the package toward said tube comprising a pair of rotatably mounted tension screws, a cross frame adjustably mounted thereon, a package engaging member supported from said cross frame and a pressure 90 screw interposed between said member and frame.
39. In a package filling machine a package support comprising a sleeve, a package contacting head adjustably mounted therein, 95 means for adjusting said head in position therein said head being forked to engage the package at a plurality of points.
40. In a package filling machine a package support comprising a sleeve, a package 100 contacting head adjustably mounted therein, means for adjusting said head in position therein said head being forked to engage the package at a plurality of points and means for preventing rotation of said head within 105 said sleeve.
41. In a package filling machine a package support comprising a sleeve, a package contacting head adjustably mounted therein, 110 means for adjusting said head in position therein said head being forked to engage the package at a plurality of points and means for preventing rotation of said head within said sleeve, said means comprising a cross member mounted on the sleeve and a 115 lug projecting downwardly from said head in engagement therewith.
42. In a package filling machine a package support comprising a sleeve, a package contacting head adjustably mounted therein, 120 means for adjusting said head in position therein said head being forked to engage the package at a plurality of points and means for preventing rotation of said head within said sleeve, said means comprising a 125 cross member mounted on the sleeve and a

lug projecting downwardly from said head in engagement therewith, a rod screw-threaded in said cross member and in rotatable engagement with said head to support it.

5 43. In a package filling machine a high speed low pressure feeding member, a combined cut-off low speed high pressure feeding member manually operated means for first withdrawing the combined cut-off and
10 feed member from a cut-off position and subsequently throwing it into operative position

and automatic means for later stopping its movement and leaving it in the cut-off position.

In testimony whereof, I affix my signature in the presence of two witnesses this 17th day of January, 1914.

ADELMER M. BATES.

Witnesses:

GENEVA HIRTH,
MINNIE SUNDFAR.
